BOOK-END LAMP

Thomas H. Francis, New York, N. Y.

Application April 27, 1954, Serial No. 30,205

Term of patent 3½ years

(Cl. D48—20)

FIG. 1

To all whom it may concern:

Be it known that I, Thomas H. Francis, a citizen of the United States, residing at New York, in the county of New York and State of New York, have invented a new, original, and ornamental Design for a Book-End Lamp, of which the following is a specification, reference being had to the accompanying drawing, forming part thereof.

Fig. 1 is a perspective view of a book-end lamp showing my new design; and

Fig. 2 is a top plan view thereof.

I claim:

The ornamental design for a book-end lamp, substantially as shown.
